UNITED STATES PATENT OFFICE.

JAMES ROWE, OF CHICAGO, ILLINOIS.

APPARATUS FOR MELTING GLUE.

SPECIFICATION forming part of Letters Patent No. 631,327, dated August 22, 1899.

Application filed March 21, 1899. Serial No. 709,897. (No model.)

To all whom it may concern:

Be it known that I, JAMES ROWE, a citizen of the United States, residing at Chicago, in the county of Cook and State of Illinois, have 5 invented certain new and useful Improvements in Apparatus for Melting Glue; and I do hereby declare the following to be a full, clear, and exact description of the invention, such as will enable others skilled in the art to 10 which it appertains to make and use the same.

My invention relates to a novel apparatus for melting glue, glue compositions, and similar substances, the object being to provide a device of this character in which the glue can 15 be readily melted without the addition of an undesirable quantity of water, so that it can be readily used for the manufacture of printers' rollers; and it consists in the features of construction and combinations of parts here- 20 inafter fully described and claimed.

In the accompanying drawings, illustrating an apparatus constructed in accordance with my invention, Figure 1 is a transverse sectional view of same on the line 1 1 of Fig. 2. 25 Fig. 2 is a longitudinal section on the line 2 2 of Fig. 1. Fig. 3 is a detail sectional view on the line 3 3 of Fig. 1.

In melting glue or similar substances preparatory to using it in the manufacture of 30 printers' rollers and other purposes it is essential that the minimum quantity of water be added thereto, as if the percentage of moisture is only slightly too great it cannot be successfully used for this purpose. To 35 this end it is customary to melt such glue by placing it in a closed receptacle and admitting steam to the latter, whereby the glue is melted and only a very small percentage of moisture added. In order to successfully 40 melt said glue to a uniform condition, it is necessary that it be divided into small pieces, so that the steam can readily act thereon and melt it more rapidly than would be possible with a larger mass. This has heretofore been 45 most successfully accomplished by placing such glue in wire baskets, through the interstices in which the molten glue could find exit. This process is, however, objectionable, inasmuch as after a given time the en- 50 tire quantity of glue contained in a basket packs together and forms a mass which cannot be readily acted upon by the steam. To over-

come this and other objections, I have de- 55 signed my apparatus to agitate the glue and keep it in constant motion in the presence of steam, whereby each piece will be acted upon uniformly and packing will be entirely pre- 60 vented, thus saving time and likewise avoiding the addition of a superfluous amount of moisture to the glue.

The machine for carrying out my process 65 consists of a preferably cylindrical casing A, having a hinged cover B. A shaft C passes centrally through said casing A and is journaled in bearings D in the end walls of same. Said shaft C carries a cylinder E, rigidly mounted thereon and consisting of the annularly-flanged end plates F, in which the ends of a wire-cloth cylinder G are secured. Said cylinder G is provided with a gate H, through 70 which the glue is introduced and which is then closed and locked by means of the latch I. At one of its projecting ends said shaft C carries a pulley J, by means of which said shaft and cylinder are revolved. As said bearings D 75 are located below the lower edge of the cover B and must be preferably made removable, together with the cylinder G, I have provided vertical slots in the end plates of the casing A, extending from the upper edge thereof to 80 said bearings, said slots being adapted to be closed by means of plates K, having side grooves adapted to receive the edges of said end plates. Said plates K are provided at their lower ends with semicircular recesses 85 to receive the shaft C. On the interior of the said casing A, in the lower portion thereof, I form steam-boxes L by means of securing plates M therein, said plates being of irregular shape in cross-section and secured at their 90 upper and lower edges to the inner face of said casing A, their general formation being such that a space is left between the same and said casing to form said steam-boxes L. Steam is admitted to said boxes through the 95 pipes N and flows thence into said casing A through the longitudinal slots O in said plates M, flanges P being provided adjacent said slots to cause the steam passing through the same to impinge against the cylinder G. A 100 pipe Q, leading from the cover B, affords an outlet for the steam after passing through the cylinder G. The molten glue drips from said cylinder G upon the lower inclined por-

tions of the plates M and flows out through the pipe R, leading from the bottom of said casing A. To prevent water from condensed steam from mixing with the molten glue, I
5 have provided troughs S, mounted on said plates M above said slots O and extending the entire length of the casing A. The said troughs S are adapted to collect the condensations forming in the upper portions of said
10 casing and lead the same to pipes T, entering said casing A at one end, said pipes T being preferably brought together at their ends and connected with a waste-pipe U.

I claim as my invention—

- 15 1. A device for melting glue comprising a casing having a removable cover, a perforated cylinder revolvably and removably mounted in said casing and adapted to receive lumps of glue, means for revolving said cylinder,
20 steam-boxes in said casing, slots connecting said steam-boxes with the interior of said casing, said slots being so directed as to cause the steam to enter said casing in sheets practically radial with said revoluble cylinder,
25 steam-inlets in said boxes, a steam-outlet from said casing, and an outlet for molten glue.
2. A device for melting glue comprising a casing having a removable cover, a perforated cylinder revolvably and removably mounted
30 in said casing and adapted to receive lumps

of glue, means for revolving said cylinder, steam-boxes in said casing, slots connecting said steam-boxes with the interior of said casing, troughs interiorly mounted in said casing above said slots and adapted to collect 35 water from condensed steam, a waste-pipe connected with said troughs, steam-inlets in said steam-boxes, a steam-outlet from said casing, and an outlet for molten glue.

3. A device for melting glue comprising a 40 casing having a removable cover, a perforated cylinder revolvably and removably mounted in said casing, and adapted to receive lumps of glue, means for revolving said cylinder, steam-boxes in said casing, slots connecting 45 said steam-boxes with the interior of said casing, said slots being so formed as to cause steam issuing therefrom to impinge against said cylinder, troughs interiorly mounted in said casing above said slots and adapted to 50 collect water from condensed steam, a waste-pipe connected with said troughs, steam-inlets in said steam-boxes, a steam-outlet from said casing, and an outlet for molten glue.

In testimony whereof I affix my signature 55 in presence of two witnesses.

JAMES ROWE.
